CONTAINER FOR EXPLOSIVES

Jack Edward Hodgson and Eugene Victor Abel,
Memphis, Tenn., assignors to Continental Can
Company, Inc., New York, N. Y., a corporation
of New York

Application August 12, 1943, Serial No. 498,386

3 Claims. (Cl. 102—24)

1

This invention relates to a container for explosives which is employed for packing, storing and handling of the explosive, and also includes parts whereby the explosive may be prepared for detonation without opening the container.

In such a container it is desirable that the package be maintained as a unit, and the service of attaching a detonating agent should be confined to a minimum of manipulation. Furthermore, it is often desirable that the container should be of relatively light and thin material and hence any openings would constitute a weakness in the structure; and a feature of the present invention is the inclusion of means whereby necessary openings are compensated by reinforcing material.

A further feature of the invention is the provision of a structure which can be easily and simply manufactured and can be made to enclose the explosive in a sealed and weather-tight condition.

An illustrative form of the package is shown in the accompanying drawings:

Figure 1 is a perspective view of the filled and sealed container.

Figure 2 is a longitudinal sectional view on an enlarged scale substantially on line 2—2 of Figure 3.

Figure 3 is a transverse sectional view substantially on line 3—3 of Figure 2.

The container is illustrated as formed of a body 10, which may be of sheet metal such as tin plate, having the ends of the seam edges of the blank joined by a body seam 11 in the usual way. The ends 12, 13 are illustrated as of slip type for engaging around the ends of the body 10, but it will be understood that these ends may be formed in another manner for assembling to the body by other means. When the explosive is subject to variation in contact with moisture or other air conditions, it is preferred to complete a hermetic seal by sealing means 14, which, for an explosive that is not sensitive to soldering temperatures, may be provided by a soldering operation.

The body is illustrated as provided with apertures 16, 17. In the illustrated form, the aperture 16 is of lesser length than the aperture 17. These apertures are located remote from the ends of the container, so that they remain easily accessible.

A plate 20 of heavier material, such as steel, is secured to the body at the inner surface thereof, and is sealed to this body. It has been found that soldering or brazing secures an adequate

2

attachment and seal. This plate 20 has a longitudinal slot therein terminating short of its ends and illustrated as having a length equal to the distance between the outer ends of the holes 16, 17.

The plate 20 receives a member 21 which has a rib 22 projecting therefrom inwardly into the space within the container body 10. The ends and longitudinal edges of the member 21 are engaged with the plate 20, and are secured and sealed thereto as for example by a soldering operation. It will be noted from Figure 2 that this rib provides a trough co-extensive with the slot in the plate 20. This trough is closed by the adjacent parts of the body wall, except at the openings 16, 17, so that a tunnel is formed which is sealed from the interior of the container and has closed ends, but communicates with the exterior through the openings 16, 17, which are located laterally of the axis of the tunnel so that in introducing a fuse cord, this cord must be bent at the openings in order to pass it into and through the tunnel.

When the body 10 has been assembled with an end 13, it can be filled with the explosive and then the other end 12 applied. Upon sealing, the package is hermetically-proofed against atmospheric influence.

In using the container of explosive, a fuse such as a detonating fuse is inserted through either aperture 16, 17 and passed along the tunnel formed by the member 22 and the inner surface of the body 10. Upon detonation of the detonating fuse, the explosive effect is transmitted through the wall provided by the member 22 and thus detonates the charge of explosive, with or without causing rupture of this wall prior to the detonation.

It will be noted that the plate 20 serves for reinforcing the body 10 at the region of apertures 16, 17 by preventing distortion of the body such as by an inward movement to collapse the tunnel whereby trouble would be encountered in introducing the fuse, and also serves to reinforce the body at the moment of ignition and provides assurance that a maximum effect will be applied to the inner wall of the member 21 to detonate the charge.

In the illustrated form, two openings 16, 17 have been illustrated, thus providing a structure in which two detonating fuses may be employed for assuring detonation, or the openings may be employed for the passage of a single length of detonating fuse which is used for detonating a

number of the containers with essential simultaneity. By having the aperture 17 of proper length, it is feasible to employ time fuses and detonating caps in lieu of the detonating fuse when so desired: while the short opening 16 conditions a relatively short angle in the detonating fuse when the container has been serviced for detonation, so that the detonating fuse will not slip from position.

It is obvious that the invention is not limited to the form of construction shown, but may be employed in many ways in the scope of the claims.

We claim:

1. An explosive container comprising a body and ends closing the same, said body having longitudinally spaced openings therein, one of said openings being of a length to receive a detonating cap and another opening being shorter, and an internal plate attached and sealed to the body and closing the openings, said plate having an inwardly projecting rib within its area, said rib extending longitudinally of the body and providing with the adjacent parts of the body a tunnel which is closed at its ends and is sealed from the interior of the container and communicates with the exterior through said openings, said openings and tunnel being constructed and arranged to permit a length of fuse cord to be passed through the tunnel from opening to opening with the walls of the openings and tunnel effective to maintain bends in the fuse cord at said openings whereby the fuse cord is held against slipping from position.

2. An explosive container comprising a body and ends closing the same, said body being of light sheet metal and having an opening therein remote from its ends, an internal plate of heavy metal attached and sealed to said body for reinforcing the body at the region including said opening, said plate having a slot extending longitudinally of the body with one part of its length aligned with said opening, and a thin sheet metal member with an inwardly projecting rib formed

therein and terminating short of its ends, the edges and ends of said member being attached and sealed to said plate with said rib providing an outwardly directed trough lying along said slot, the said attachments and seals being effective to close communication between the interior and exterior of the container through said opening, said trough cooperating with the inner surface of the body for providing a tunnel closed at its ends and extending from the opening for receiving a fuse cord introduced through said opening.

3. An explosive container comprising a body and ends closing the same, said body having openings therein spaced longitudinally from one another and from the ends of the body, and an internal plate attached and sealed to the body and closing said openings, said plate having an inwardly projecting rib within its area and providing with the overlying portion of the body wall a tunnel extending longitudinally of the body and between and communicating with the exterior through said openings, through which openings and tunnel a fuse cord may be passed with the cord bent at the openings and with the angle in the cord at an opening effective to prevent slippage of the fuse cord from position.
